METHOD AND APPARATUS FOR DIVIDING
PULVEROUS MATERIAL INTO DESIRED
FRACTIONS BY MEANS OF A ROTATING
SIFTING MACHINE

Karl-Axel Göran Gustavsson, Enkoping, Sweden

Application July 15, 1948, Serial No. 38,806
In Sweden February 23, 1948

10 Claims. (Cl. 209—145)

1

The present invention relates to a method and an apparatus for dividing pulverous material into desired fractions and the invention is an improvement and development of the method in which the division into fractions is carried out in a wind sifting machine having a rotating sifting chamber and in which the material while exposed to centrifugal action is subject to the action of a rotating gas current controllable as to capacity and velocity and flowing towards the centre in a direction opposite to the centrifugal force.

In this method it has been proved that the air flowing spirally into the sifting chamber of the wind sifting machine is subject to a retardation close to the walls of the sifting chamber causing, especially in apparatus of small dimensions, a certain impurity in the produced fractions.

According to the invention this disadvantage is eliminated by causing the sifting chamber of the wind sifting machine to rotate with a number of revolutions so adapted that the gas current flowing spirally inwards at a certain radial distance from the centre of rotation of the sifting chamber obtains the same tangential velocity as the walls of the sifting chamber at this point and by introducing the pulverous material into the sifting chamber at or near this point. Thus, the tangential velocity of the walls and the gas flow are synchronized at this point in the determining zone of the sifting chamber in which the particles according to their centrifugal velocity are either carried in towards the centre or out towards the periphery.

Other characteristics of the invention will be further described in the following with reference to the embodiment illustrated in the accompanying drawing in which 1 designates an electric motor carried by the frame 2. The entire sifting machine is mounted on the motor shaft 3 so that every part of the machine is rotated at the same speed. The sifting machine consists of a housing 6 provided with two collecting chambers 4 and 5. At the bottom of the housing 6 there is an air inlet 8 provided with an adjustable choking member 7. The housing carries a disk 9 by means of a number of annular plates 10, arranged one above the other and adapted to cause a uniform flow of the air passing to the sifting chamber. Close above the disk 9 a second disk 11 is arranged so as to form between the two disks an unbroken slit 13, having a central inlet 12 and a circumferential discharge opening 18 for the material. A third disk 14 projects radially from the housing 6 over the disk 11 forming the

2

sifting chamber 20 between said disk 14 on one side and the disks 9 and 11 on the other side. A fan is formed on the opposite side of said disk 14 by means of a number of blades 17 and a disk 16 integral with the disk 11 through the hub 15. The sifting chamber communicates with the space in which the fan is disposed through an annular passage 23.

The radial distance from the centre of the discharge opening 18 is so arranged in proportion to other dimensions of the apparatus and with respect to the speed of the motor, that the tangential velocity of the air current in the sifting chamber drawn spirally towards the centre by means of the fan 14, 16, 17 substantially corresponds to the tangential velocity of the disks 9, 11 at the discharge opening 18.

The disturbances in the air current caused by the friction against the walls of the sifting chamber at the point where the material is introduced are eliminated by this device. As previously stated this is of special importance as the particles should not be subject to any more or less uncontrollable forces at this point.

The material which is fed through the stationary funnel 19 is drawn through the central charge opening 12 and by centrifugal force symmetrically thrown out through the unbroken slit 13 to the discharge opening 18. A certain amount of transportation air may also be drawn through the charge opening 12. The air flow rectifier 10 which naturally may be constructed in many other ways, for instance with vertical slots or as a perforated disk, a wire netting or the like, causes a symmetrical and uniform flow of air, besides allowing the air to reach the desired tangential velocity under a relatively low velocity in radial direction before it is introduced in the sifting chamber 20.

The coarse fraction of the pulverous material, which is thrown out of the sifting chamber during sifting is collected in the chamber 4, in which it is pressed fast against the outer wall by centrifugal force and from which wall it may be knocked down into the trough 21. The finer fraction which is conveyed through the fan is discharged by centrifugal force into the chamber 5 having such dimensions that the radial and axial components of the air velocity are small enough to allow the pulverous material to lodge on the outer walls of the chamber. After being knocked down into the trough 22 the material may be removed and exposed to weighing and microscopic examination. By also weighing the

coarser fraction the sifting losses may be established.

The main quantity of air for the sifting is drawn in through the central inlet opening 8. In order to obtain the desired fractions the capacity of the air flow is controlled by the adjustable choking member 7.

The unbroken slit 18 should preferably have such a small axial extent that the mixture of pulverulent and air by friction against the walls of the slit is brought into a rotation, which when the mixture is introduced into the sifting chamber substantially corresponds to the rotation of the air in the sifting chamber.

Having now particularly described the nature of my invention and the manner of its operation, what I claim is:

1. In an air separator for grading finely divided material in lights and heavies, the combination of a pair of plate members mounted for rotation about a common axis and disposed parallel to each other and spaced apart to form an annular substantially slit-shaped separation chamber between the plate members, drive means for rotating said plate members, conduit means for admitting air into said chamber along the circumference thereof, guide means rotatable about said rotational axis and included in said conduit means, said guide means including a plurality of guide elements arranged to divide the airflow in a plurality of substantially parallel aircurrents for imparting air flowing through said conduit means, an approximately uniform rotational velocity about said rotational axis approximately equal to the rotational velocity of said plate members about the said axis, suction means communicating with said chamber through a port in one of the plate members near the rotational axis of the latter for producing a spiral flow of air through the chamber toward the rotational axis thereof, the other of said plate members including a circular slit having an inlet port, feed means communicating with said inlet port for delivering material to be graded into said circular slit, the said plate member further including an annular outlet port communicating with the slit therein and the separating chamber for delivering material from the slit into the said chamber, said annular slit outlet being disposed at a radial distance from the rotational axis at which distance the tangential velocity of the air flowing in spirals through the separating chamber corresponds approximately to the rotational velocity of the plate member portions defining the said slit outlet, and a settling chamber encompassing the circumference of the separating chamber for collecting heavies ejected from the separating chamber by centrifugal force, the lights being discharged from the separating chamber through said port thereof near the rotational axis.

2. An air separator as described in claim 1, wherein the said guide elements comprise a plurality of annular discs mounted for conjoint rotation about said rotational axis and disposed parallel to each other spaced apart.

3. An air separator as described in claim 1, wherein said suction means comprise a centrifugal fan having fan blades mounted for rotation about said rotational axis and disposed behind the separating chamber as seen in the direction of the airflow.

4. An air separator as described in claim 1, in combination with a third plate member

mounted adjacent to and spaced apart from the plate member having said port near the rotational axis to form an annual chamber between the said plate member and the third plate member, and fan blades mounted for rotation about said rotational axis and disposed within said last mentioned annual chamber, said fan blades being set for drawing air through the said plate port.

5. An air separator as described in claim 1, in combination with a second settling chamber disposed on the discharge side of said suction means for collecting the light passing through the suction means.

6. An air separator as described in claim 1, in combination with a third plate member mounted adjacent to and spaced apart from the plate member having said port near the rotational axis to form an annual chamber between the said plate member and the third plate member, fan blades mounted for rotation about said rotational axis and disposed within said last mentioned annual chamber, said fan blades being set for drawing air through the said inlet port, and a second settling chamber encompassing the said annual fan chamber for collecting the lights of the material to be graded.

7. An air separator as described in claim 1, in combination with a choke member adjustably mounted within said conduit means for regulating the airflow rate through said conduit means.

8. An air separator for grading finely divided material in lights and heavies, comprising a shell mounted rotatably about an axis, drive means for rotating shell, said shell including an annular comparatively narrow separating chamber extending radially from the shell axis and mounted for rotation in unison with the shell concentrically with the shell axis, said chamber being open along its circumference and having an air outlet radially spaced from the circumference of the chamber, said shell further including an air inlet for admitting operational air into the shell and conduit means for admitting air into said chamber along the circumference thereof, pump means for circulating an air current through said shell in the direction from the air inlet to the air outlet, guide means disposed within said conduit means and mounted for rotation in unison with the shell and the conduit means, said guide means comprising a plurality of guide elements arranged to divide the airflow in a plurality of substantially parallel air currents for imparting to the airflow through said conduit means a substantially uniform rotational velocity about the shell axis approximately equal to the rotational velocity of the shell, conduit means for admitting material to be graded into the separating chamber, said conduit means communicating with the chamber through an inlet port for the material positioned intermediate the chamber circumference and the air outlet of the chamber and at a radial distance from the shell axis at which distance the tangential velocity of air flowing spirally through the separating chamber toward the air outlet thereof corresponds approximately to the rotational velocity of the said inlet port for the material, and a settling chamber encompassing the circumference of the separating chamber for collecting heavies ejected from the separating chamber by centrifugal force, the lights being discharged from the separating chamber through said outlet port thereof.

9. An air separator as described in claim 1,

wherein said inlet port for the delivery of material is positioned substantially in alignment with said rotational axis.

10. An air separator as described in claim 8, wherein said drive means comprise an electric motor having a drive shaft protruding therefrom, said shell being operatively coupled with said shaft with the shell axis in vertical position for rotation of the shell and the components disposed therein by the motor.
